UNITED STATES PATENT OFFICE.

CHARLES E. LEE, OF NASHUA, AND WILLIAM C. HOYT, OF MERRIMAC, NEW HAMPSHIRE.

SEAL-LOCK.

SPECIFICATION forming part of Letters Patent No. 591,407, dated October 12, 1897.

Application filed June 21, 1897. Serial No. 641,592. (No model.)

To all whom it may concern:

Be it known that we, CHARLES E. LEE, residing in Nashua, and WILLIAM C. HOYT, residing in Merrimac, county of Hillsborough, 5 State of New Hampshire, citizens of the United States, have invented new and useful Improvements in Freight-Car Seals, of which the following is a specification.

This is an improved seal adapted especially 10 for use on freight-cars, although it may be applied to any receptacle containing merchandise in transportation where it will be of service.

It has for its principal objects, first, to provide perfect legibility, thus obviating a great 15 objection to ordinary lead seals; second, to render it impossible that the seal should be tampered with without destroying it; third, to make the seal sufficiently strong to prevent 20 accidental breakage, and, fourth, to construct a seal having the above-named advantages economically.

The nature of our invention is fully described below, and illustrated in the accompanying drawings, in which—

Figure 1 is an elevation of our improved device applied to a freight-car, portions of the door and jamb of the car being shown. Fig. 2 is a horizontal section taken on line 30 2, Fig. 1. Fig. 3 is a plan view of the seal proper or tag removed.

Similar letters of reference indicate corresponding parts.

A represents a portion of the door of a 35 freight-car, and B a portion of the jamb.

C is a horizontal plate secured to the door A by suitable bolts *a* and held by nuts *a'*, applied on the inside of the door. This plate or base is formed with two transverse bridges 40 D and E. The object of the bridge D is to conceal the "consecutive number" on the seal or tag, as below described, and the object of the bridge E is to conceal the bolt or latch F, Fig. 2, which projects normally into 45 the space between the plate and the bridge E by means of a spring *f*, which encircles the shank *F'* of the bolt between said bolt and the washer *g*. Provision is made for this latch or bolt by forming a tubular chamber 50 C' on and extending rearward from the plate C into a suitable recess constructed in the

door. A staple H is secured in the jamb B by bolts on the inside of said jamb, and extends into the recess B', with its central portion in a vertical position. A bolt K swings 55 loosely horizontally on said staple and is adapted to move vertically thereon. This bolt is provided with a neck K' between its main portion and the head K".

The seal proper or tag L consists of a strip 60 of metal, preferably tin, formed, preferably, but not necessarily, with the inwardly-projecting stiffening-lips L'. Near one end of the seal a longitudinal slot P is formed, broadened at its inner end at P' to receive the head 65 of the bolt K. Between the slot and the other end of the seal is the number of the station from which the car thus sealed is sent, in this instance "B & A 1217," and what is termed the "consecutive number"— 70 that is to say, the private number designating this particular seal, in this instance "375."

In practical operation when a car is to be sent from certain station on a certain road, such as the particular station or town known 75 as "B & A 1217," by the official who uses the consecutive number "375," the marks "B & A 1217" and "375" are stamped on or otherwise applied upon the outer surface of the seal or tag L. In the drawings these marks 80 are in raised letters. The tag is then placed over and around the bolt K by means of the broad end P' of the slot P, and its end slid under the bridge E, pressing back the latch F, whose beveled edge faces the approaching 85 seal or tag. When the portion P' of the slot reaches the latch, said latch slips through it and locks the tag or seal securely, the neck K of the bolt K' lying in the slot P next its outer end. In this position the station number 90 is in plain sight between the bridges E and D, the consecutive number is concealed by the bridge D, and the latch or bolt F is concealed by the bridge E.

It is evident that the seal L cannot be withdrawn without destroying it or utterly breaking the apparatus. Hence tampering with it without detection is practically impossible. It is also impossible to gain access to the consecutive number without destroying the seal. 100 When the car has reached its destination, the seal or tag L is cut and withdrawn from the

rear end and filed away for reference. Longitudinal, vertical, and lateral relative motion of the bolt K and seal L are provided for by the swinging and vertical play of said bolt 5 on the staple H.

It will readily be seen that as the characters on this seal may be printed thereon or punched or perforated therein there is no danger of illegibility, as is the case in lead seals with impressions stamped thereon. The strength of 10 the seal is sufficient to prevent accidental breakage, and its economy when made by the quantity is apparent. It may be applied not only to freight-cars, but to packages or receptacles of any kind for containing merchandise in transit.

If desired, a supplemental card or tag may be secured to the seal L by means of the lips L', and have printed upon it the characters 20 above mentioned as being applied directly to the seal.

The device may be used in sealing goods not only in transportation, but in storage, bond, &c.

25 Having thus fully described our invention, what we claim, and desire to secure by Letters Patent, is—

1. In an apparatus for sealing freight-cars and other receptacles for merchandise, a seal 30 or tag consisting of the metallic strip L provided with the longitudinal slot P formed with an enlarged end P', said strip being provided with suitable characters identifying the seal; a locking device adapted to be secured to the door or opening portion of the receptacle, and provided with a bolt adapted to extend through the enlarged portion of said slot in the seal; a bridge formed on said locking device and extending over and concealing the bolt; and a securing device extending 35 from the jamb or body portion of the receptacle through and over the edges of said slot in the seal, substantially as set forth.

2. In an apparatus for sealing freight-cars and other receptacles for merchandise, a seal 45 or tag consisting of the metallic strip L provided with the longitudinal slot P formed with an enlarged end P', said strip being provided with suitable characters identifying the seal; a locking device adapted to be secured 50 to the door or opening portion of the receptacle, and provided with a bolt adapted to extend through the enlarged portion of said slot in the seal; a bridge formed on said locking device and extending over and concealing the bolt; the staple H secured to the jamb or body portion of the receptacle; and the bolt K loose upon said staple and adapted to both swing and slide thereon, said bolt being formed with the neck K' and head K" for engagement with said slot in the seal, substantially as described.

3. In an apparatus for sealing freight-cars and other receptacles for merchandise, a seal 60 or tag consisting of the metallic strip L provided with the longitudinal slot P formed with an enlarged end P', said strip being provided with suitable characters identifying the seal; a locking device adapted to be secured to the door or opening portion of the receptacle, and provided with a bolt adapted to extend through the enlarged portion of said slot in the seal; a bridge formed on said locking device and extending over and concealing the bolt; a second bridge formed on the 70 locking device and extending over and concealing the private characters thereon; and a securing device extending from the jamb or body portion of the receptacle through and over the edges of said slot in the seal, substantially as set forth.
